PRESSING IRON

Maurice Victor, London, England

Application August 9, 1950, Serial No. 178,377

Claims priority, application Great Britain
November 24, 1949

2 Claims. (Cl. 38—79)

1

This invention relates to pressing irons incorporating their own heating means such as an electrical resistance or gas heating means, and in which the iron has a weight bias at one end so that when hand pressure is released therefrom the sole of the iron will be moved upwards away from the work so that when the iron is not in use the sole will not make contact with the work.

An object of the present invention is to obtain a highly efficient counter-weighting means which has the effect of tilting the sole upwardly away from the work when hand pressure is released from the handle of the iron but which obviates embodying bulky or weight mass within the up-standing trailing part of the iron.

Another object of the present invention is to provide an iron with the said counter-weighting means and in which said means is so connected to the iron that it acts as a lever having a fulcrum point in close proximity to an insulated heel extension of the sole of the iron to enable a neat, compact and highly efficient tilting means and iron to be provided.

A further object of the invention is to provide the said counter-weighting means in a form in which it can be displaced relative to the iron into an operative position spaced rearwardly of the iron whilst the iron is in use for producing the aforesaid upward tilting of the sole when hand pressure is released from the handle of the iron but can be folded closer to the iron when the iron is to be put away out of use.

The aforesaid relative folding of the counter-weighting means can be obtained by suitably loading the free end of an arm pivoted to a trailing part of the iron. Also, if desired this pivoted arm may be adapted to actuate a switch when the iron is an electrically heated type so that the iron can only be connected to the source of electrical energy when the arm is swung to the position in which the counter-weighting means become effective for tilting the sole of the iron away from the work.

Other advantages and objects of the invention will be apparent by reference to the accompanying drawings appended hereto and illustrating embodiments thereof, and wherein,

Figure 1 is a side elevation view showing the foldable counter-weighting means collapsed to the out of use position but showing the manner in which it can be adjusted to the operative position in broken line, the manner of the tilting of the iron also being shown in broken line.

Figure 2 is a plan view of Figure 1.

2

Figure 3 is a section on the line III—III of Figure 1.

Figure 4 is a broken sectional elevation also taken on the line III—III of Figure 1 but showing how the counter-weighted arm can be adapted to operate a switch, and;

Figure 5 is a side elevation view of a modification in which an air gap is provided between the heel of the sole plate of the iron and the part on which the iron rests when tilted to the out-of-use position.

Referring to the drawings, the normal sole plate for engaging the work is indicated by the reference numeral 1 and comprises the base of a hollow body part 2 accommodating the heating means, this body part 2 having formed in prolongation therewith a relatively light hollow upwardly and rearwardly inclined trailing part 3, these parts 2 and 3 preferably being formed in curvilinear continuity with each other so as to obtain a clean streamlined effect of the total body of the iron. An insulating handle 4 bridges the parts 2 and 3, and this handle 4, as shown, is preferably formed somewhat in continuity with the nose of the body part 2 and has a trailing portion which merges neatly into the rear part of the hollow portion 3.

The base of the trailing part 3 is closed by a cover plate 5 comprising the heel of the iron and composed of a material of low heat conductivity, and its lower or front corner 5' is slightly curved or bevelled to form a fulcrum point about which the iron will tilt when hand pressure is released therefrom following an ironing operation, whereby the iron will tilt to the position shown in broken lines and be supported upon the insulating plate 5. That is to say the lower or front corner of the plate 5 can form a fulcrum region about which the iron will tilt, and if desired the heel plate 5 and sole 1 can be shaped so as to merge neatly one into the other in continuity so that the said fulcrum region is formed at the junction of the heel plate 5 and sole 1.

As distinct from the previously proposed counterweighted iron adapted to be tilted upwardly when hand pressure is released therefrom, the weighted mass to produce this tilting action is carried by means which enables the weighted mass to be situated well in rear of and above the sole 1 without having an ungainly trailing portion 3. In the embodiment illustrated this result is obtained by locating the weighted mass within the free end of an arm 6 which is preferably of elongated U form so that it can be

3

folded neatly about the handle 4 in juxtaposition to the body part 2 when the iron is not in use.

The said elongated U-shaped arm 6 can be of any suitable cross-section and by way of convenience it is shown as being of tubular form, i. e. a length of metal tubing with its side limbs flattened as at 6' to afford good bearing surfaces to rock against bosses 7 formed on the side cheeks of the trailing part 3 in juxtaposition to the corner 5' of the heel plate 5, these bosses and the flattened parts of the arms receiving pivot pins 8 threaded into the bosses but having outer end parts formed cylindrically so that the flattened parts 6' can rotate thereon as shown in Figure 3, the heads of the pins 8 securing the arm 6 in position.

The flattened parts 6' of the arm 6 can be solid as shown and united to the tubular part of the arm by any suitable means.

The counter-weighting means can be cast into the bend of the U or can comprise a U-shaped portion 6a across tubular or other suitable section side limbs of the U-shaped arm 6, this U-shaped portion 6a being composed of a heavy metal of sufficient mass to produce the desired counter-weight operation when the arm 6 is swung away from its folded away position to substantially the position shown in broken line in Figure 1, the movement of the arm 6 into this operative position being limited by abutments 9 formed integral with the trailing portion 3. Spring fingers 9' can trip over the U-shaped member 6 when folded back to the operative position to secure the arm against unintentional forward folding when in use.

If desired the swinging movement of the arm 6 into the raised or operative position can be adapted to operate a switch 10 as shown in Figure 4, this switch being accommodated within the housing portion 2 and operated from a finger or trigger member 11 or other suitable means driven from one of the two pivot pins which is indicated by the reference numeral 8', this particular pivot pin being journaled within the boss 7 and having a square or other suitable portion 8a engaged in a correspondingly shaped hole in the appropriate limb 6' of the arm 6. Nuts 12 can be threaded on the pin 8' beyond the boss 7 to locate the pin against axial displacement.

The cable for connecting the heating means to the source of electrical energy is carried through a flexible rubber tube 13 united to the upper portion of the trailing part 3.

In the embodiment shown in Figure 5 an iron has its handle 4' securely affixed to the iron only at the front end, the trailing part of the handle being flared into a heel forming face 14 on to which the iron is tilted when the U-shaped counter-weight arm 6 takes charge and tilts the iron to the out-of-use position. The arm is pivoted to flat-faced bosses formed on the handle, a pivot pin or pair of screws 15 passing through the flattened inner ends 6' of the arm 6. A pair of side webs 16 form riding surfaces for the flattened ends of the arm 6 and each web has a step 17 to act as an abutment for the arm, whilst

4

each flattened portion 6' can be formed with a dimple 18 to trip into a shallow depression in the associated web to firmly locate the arm 6 in the operative position.

The heel forming trailing face 14 of the handle 4' is shaped and directed relative to the sole 1' so as to extend substantially in continuity with the trailing radiused corner 1a of the sole, complete continuity being avoided to afford a relatively narrow air gap 14' between the heel end 14 of the handle and the corner 1a of the sole, to ensure adequate heat insulation when the iron is tilted over on to the heel 14 under the influence of the weight 6a.

I claim:

1. In a pressing iron a hand-grip handle extending from the toe of the iron to beyond the rear of the sole of the iron, an insulating heel provided on the rear face of said handle on which the iron is supported when hand pressure is released from the iron, the said heel having an upwardly and rearwardly inclined face in substantial continuity with the sole of the iron, a lever arm of elongated U form pivoted at one end to opposite sides of the iron in juxtaposition to said heel and the rear of the sole, said lever arm being dimensioned to fold over the handle with its other end close to the toe of the iron when the latter is out of use, and a counter-weight carried by said other end of said lever arm so that when the arm is in use the counter-weighting mass is disposed above the handle and in rear of said heel, thereby causing the iron to tilt on to said heel so as to raise the sole from the work when hand pressure is removed from the iron.

2. A pressing iron comprising a body part member, a sole on said body part, an insulated handle member directly secured at its front end to the toe end of the body part member, said handle member being bent downwardly towards the rear of the iron and overhanging the rear of the sole of the said body member, and being narrowly spaced from said sole to afford an air gap, a heel provided on the rear extremity of the handle member extending upwardly and rearwardly away from the rear of the sole so as to extend substantially in continuity with the sole and afford a supporting surface on to which the iron will rock and be supported when hand pressure is released from the pressing iron, an upwardly and rearwardly directed lever arm connected with its lower end to the said rear part of said handle member, and a counter-balance weight at the upper end of the said arm and having a mass such that when hand pressure is released from the iron it will tilt the iron so that it stands on said heel.
